UNITED STATES PATENT OFFICE.

GEORGE DAVIS, OF ELIZABETH, NEW JERSEY.

FEED-REGULATOR FOR HEMP DRAWING AND SPINNING MACHINES.

SPECIFICATION forming part of Letters Patent No. 326,723, dated September 22, 1885.

Application filed December 3, 1884. (No model.)

To all whom it may concern:

Be it known that I, GEORGE DAVIS, of Elizabeth, in the county of Union and State of New Jersey, have invented a new and Improved Feed-Regulator for Hemp Drawing and Spinning Machines, of which the following is a full, clear, and exact description.

Reference is to be had to the accompanying drawings, forming a part of this specification, in which similar letters of reference indicate corresponding parts in both the figures.

Figure 1 is a side elevation of a part of a hemp-drawing machine to which my improvement has been applied, part being broken away. Fig. 2 is a side elevation of the brake-wheel, the side plate being removed, and the shaft and sleeve being shown in section. Fig. 3 is a sectional plan view of the brake-wheel and its attachments, taken through the line *xx*, Fig. 2.

20 The object of this invention is to provide feed-regulators for hemp drawing and spinning machines constructed in such a manner as to readily control the delivery of the sliver to the condenser.

25 The invention relates to a feed-regulator for hemp drawing and spinning machines constructed with the drive-shaft and the drive-pulley connected with the condenser-standard by a train of gear-wheels, a loose brake-wheel, and a brake-strap.

30 The condenser-standard is provided with an arm, and the brake-strap is provided with an arm having a suspended weight and a projecting pin, whereby the said parts are connected and the movements of the condenser-standard are made to control the drive-pulley of the machine, as will be hereinafter fully described and then claimed.

35 A represents the frame of a hemp-drawing machine. B is the endless chain of gill-pins, by which the sliver is delivered or fed to the condenser C. The condenser C is attached to the upper end of a standard, D, the lower end of which is hinged to a bracket or arm, E, attached to the frame A or to some other suitable support. The condenser C is held against the pull of the sliver by a spring, F, attached at one end to the standard D, and at the other end to the frame A, and its movement or play 40 is limited by a slotted stop, G, attached to the said frame A, and through the slot of which the said standard D passes.

The machine is driven from any convenient power by an endless belt, H, which passes around a pulley, I, rigidly attached to one end 55 of the shaft J.

Upon the shaft J and side by side are placed two unequal gear-wheels, K L, the hubs of which are made long and project in opposite directions to serve as bearings for the hollow 60 brake-wheel M. The hub of the larger gear-wheel K is secured, by a set-screw, N, or other suitable means, to the shaft J, so as to be carried around by and with the said shaft in its revolution. The teeth of the gear-wheel 65 K mesh into the teeth of the gear-wheel O, which is made long and journaled on a stud or pin within the shell. The wheel O also meshes with a gear-wheel, P, journaled within the shell, which meshes in turn with the gear- 70 wheel L.

To the outer end of the hub of the gear-wheel L, at the outer side of the brake-wheel M, is rigidly attached a pulley, Q, around which passes an endless belt, R, which also passes 75 around a pulley, S, attached to the drive-roller T of the endless chain B of gill-pins.

Upon the face of the brake-wheel M rests a brake-strap, U, one end of which is hinged to a standard, V, or other support attached to 80 the frame A. The other end of the brake-strap U has a horizontally-projecting arm, W, formed upon or attached to it, which arm is provided with a number of perforations or notches to receive the suspending-link of the 85 weight X, so that the said weight can be adjusted farther from or closer to the brake-wheel M, according as it is required to have the said weight X apply the brake with more or less force. 90

To the outer end of the arm W is attached, or upon it is formed, a pin, Y, which projects laterally above an arm, Z, attached to or formed upon the condenser-standard D.

The weight X is designed to be of sufficient 95 gravity to hold the brake-wheel M stationary against the driving friction of the gear-wheels connected with it, so that the shaft J and the gear-wheel K, by means of the gear-wheels O P, will drive the gear-wheel and pulley L Q, 100 and thus give motion to the machine. With this construction, should the sliver become too large and force back the condenser C, the backward movement of the standard D will

cause the arm Z to act against the pin Y and raise the brake-strap U, releasing the brake-wheel M. Then, as the friction of the said brake-wheel M upon its bearings is less than the force required to turn the gear-wheel L and pulley Q and drive the machine, the brake-wheel M will turn the gear-wheel P, traveling around the gear-wheel L instead of turning it. As the change of the sliver in size is usually small, the outward movement of the condenser C will seldom be sufficient to fully release the brake-wheel M, so that the effect will be to slow the machine more or less, as there may be more or less increase in the size of the sliver. With this construction the pulley I will always run at the speed of the driving-belt, so that there will be no tendency to throw the belt, while at the same time the feed will be controlled automatically, and in such a manner as to produce a uniform sliver.

Having thus fully described my invention, I claim as new and desire to secure by Letters Patent—

1. The combination, with the drive-shaft J, 25 the loose brake-shell N, the gear-wheel K,

fixed to the drive-shaft, the loose gear L, the pulley Q, connected therewith, and the gears O P, connecting the said gears K L, of the condenser-standard, the inclined arm Z thereon, and the pivoted brake-strap U, having a pin, Y, 30 resting on the said inclined arm, substantially as set forth.

2. The combination, with the condenser-standard D and the inclined arm W thereon, of a brake-wheel, a drive-shaft therefor, a pivoted brake-strap, and a pin on the brake-strap resting on the said inclined arm, substantially as set forth. 35

3. The combination, with the condenser-standard D and the inclined arm Z thereon, 40 of the drive-shaft J, the brake-wheel M, the brake-strap U, having a horizontally-projecting arm, W, provided with a series of apertures, and a pin, Y, and the weight X, substantially as set forth.

GEORGE DAVIS.
